ABSTRACT OF THE DISCLOSURE

A propellant charge constituted of spaced strands of material is increased in effectiveness by tapering the strands so that they diminish in thickness in the direction of gas flow. The spaces between the strands and particularly the tapering of the strands is so effected to provide minimum passage areas. The combustion time of the charge is less than 1 second and the powder charges used have combustion rates which are substantially constant over a large range of pressures.

BRIEF DESCRIPTION OF THE DRAWING

FIG. 1 is a sectional side view of a portion of one embodiment of propellant charge according to the invention, taken along line 1—1 in FIG. 2;

FIG. 2 is an end elevation view of the charge in FIG. 1; and

FIGS. 3 and 4 are graphical representations of various parameters of the propellant charges according to the invention.

DETAILED DESCRIPTION

The present invention relates to powder propellants and an object of the invention is to provide novel powder propellants whose volume is less than that of known propellants of equivalent performance:

The maximum gain possible depends on elaborate ballistic characteristics.

The principal utilization of the propellants is in rapid-combustion propellant units where the combustion period is from a few milliseconds to 1 second.

It is known that a maximum powder load density of a propellant unit (ratio of powder mass to the inside volume of the unit) decreases for any given propellant unit when the combustion time decreases.

It follows that the charges which are the object of the present invention, offer the following advantages as compared to the known charges:

(1) The volume is reduced for a given mass of powder and given combustion time;

(2) The mass of powder is increased for a given combustion time and given volume;

(3) The combustion time is shortened for a given mass of powder and given volume;

(4) The foregoing properties can be combined, for example, by decreasing combustion time and increasing powder mass for given volume.

The aforesaid advantages are obtained with an increase of the maximum working pressure of the propellant unit, and the fluctuations of specific impulsion are zero or negligible in proportion to the overall impulsion gain.

The propellant charges, according to the invention, consequently entail an improvement in the ratio of impulsion to propellant mass.

One particular example of application is that of anti-tank missiles for which the following conditions obtain:

(a) combustion of propellant in the firing tube so as not to project the propellant gas jet onto the gunner;

(b) highest possible velocity so as to increase the range of the weapon system;

2

(c) minimum mass for the weapon system (missile and firing tube).

The adoption of a charge according to the invention permits the expectation of initial velocities of 380 to 400 meters per second for a self-propelled missile of a mass less than 2.5 kg, with total combustion inside a firing tube of a length less than 2 meters.

This is especially interesting because the initial velocity on the one hand is notably increased as against current practice and it is on the other hand supersonic. This allows adding an extra propulsion stage if necessary without the drawbacks inherent in crossing the sound barrier.

The propellant charges according to the invention are made up of strands or filaments of powder whose thickness (their smallest dimension) comprises a straight portion of uniform thickness tapering thereafter from the top downward (in the direction of gas discharge flow). The charge may conceivably consist of a single strand. The variation of thickness is the same for all the strands and defines the duration of combustion, subject to the properties of the powder composition used.

The powder strands can be either flat or coiled strips of various shape and sizes, or they may be tubular.

The advantages derived from the invention are not the result of the shape of the strands, but to the tapering in thickness and to an arrangement of the charge such that the open spaces, between strands or inside each strand, can in each section satisfy the conditions of appropriate constrictions in a plane perpendicular to the direction of flow.

This condition is defined as follows: for a pre-determined interval or space, the ratio of gaseous emission area, upstream in relation to the filaments traversing the space in question, to the area of passage must be less than K/β ; K being the constriction (ratio of total emission surface area to the surface area of the nozzle passage) and β a coefficient always greater than 1, dependent on the geometry of the charge and the composition of the powder in use.

By way of nonrestrictive example, the following processes can be used to govern the spacing of the strands; longitudinal gluing of narrow spacer tapes over only a small part of the powder area, stamping of small blisters on the powder strips, use of a built-in metal sheathing.

It is also possible to set up the powder strands with sufficient freedom for the distribution of pressures on firing to keep the spaces at their optimum value.

The powder compositions to be used have the characteristics of stable combustion in a large pressure area, defined by a maximum pressure P_1 and a minimum pressure P_2 . In this same area, the rate of combustion must not vary greatly. To the pressures P_1 and P_2 , the constrictions K_1 and K_2 respectively correspond.

Subject to the form of the strands, the powder function (development of emissive surface in terms of burned thickness) will decrease from an initial value S_1 to a final value S_2 .

According to the invention, the values S_1 and S_2 must comply with the condition:

$$\frac{S_1}{S_2} \leq \frac{K_1}{K_2} \quad (1)$$

The propellant nozzle is adapted so that at the maximum its pressure may be equal to P_1 , the pressure then decreasing to a value not less than P_2 . Since the speed of combustion is not greatly dependent on the pressure, the rate of combustion is appreciably equal to that of a steady-emission propellant.

Quite a number of powders possess the necessary characteristics, especially some double-base nitroglycerine-ni-

trocellulose with a high rate of combustion, corresponding to the most desirable case.

The following manufacturing processes for the powder strands can be used nonrestrictively.

The strands can be manufactured as strips by passing sheeting crosswise between two rollers spaced to give the required thickness. Two or more strips can be made at the same time.

It is also possible to manufacture the strips by pressing sheets lengthwise between two drums mounted on a flexible bearing. The spacing then is at a predetermined value. For example, it can be governed by the passage of two rigid lateral strips of the required profile between the drums.

The strands can be manufactured as tubes by extrusion and machining or casting.

The powder strands are then assembled for making up the propellant charge.

By way of nonrestrictive example, the manner of assembly can be by countersinking the base (the thickest end) of the strands into a rigid base.

To give a better understanding of the invention, by way of nonrestrictive example, a comparison will be made between two propellant charges of equal length, one of which is made up of strands of uniform thickness according to conventional practice, and the other of strands of tapering thickness according to the invention. It is assumed that these two charges are composed of rectangular strips of powder parallel to the propellant axis.

These strips can be flat or coiled. The charge may possibly be made up of a single spirally coiled strip.

As seen in FIGS. 1 and 2 the propulsive charge comprises a plurality of flat powder bands 2 which are embedded in an inhibitor plate 1. The generated combustion gas flows towards a tube (not shown) opposite plate 1 in the direction of the arrow.

The emissive surface due to the thickness of the strands is negligible in comparison with the area of the sides of the rectangles.

By making the best use of the propellant bore, calculations show that the volume of powder in the case of the constant emission charge is:

$$\frac{K_1 \Sigma_t e_0 l}{2\beta + e_0 K_1} \quad (2)$$

wherein:

K_1 is the initial propellant constriction

Σ_t is the area of the inside straight section of the propellant body

e_0 is the thickness of the strands

l is the length of the strands

β is the ratio of self-contraction as previously noted.

In the case of the charge according to the invention, the thickness of the strands tapers over a length b .

The condition set forth in Equation 1 becomes

$$\frac{l}{l-b} \leq \frac{K_1}{K_2}$$

giving an upper limit to b .

The condition of appropriate constriction requires that the thickness shall decrease in straight-line proportion to the length x according to the relationship:

$$e = e_0 - \frac{2\beta x}{K_1} \quad (3)$$

The linear character of this function shows that the powder-making apparatus does not present any delicate practical problem and that supervisory operations are simple.

The ratio b/l being designated by the value λ , the maximum powder volume is represented by the formula:

$$V' = K_1 \Sigma_t \frac{l \left[e_0 - \frac{\beta \lambda^2 l}{K_1} \right]}{2\beta l (1-\lambda) + e_0 K_1} \quad (4)$$

The ratio

$$G = \frac{V'}{V}$$

shows the possible obtainable gain by adopting a charge according to the invention, having the same length l and the same thickness e_0 . It is simply expressed by putting the variable:

$$R = \frac{\beta l}{K_1 e_0} \quad (5)$$

whence we obtain:

$$G = \frac{(1-\lambda^2 R)(2R+1)}{1+2R(1-\lambda)} \quad (6)$$

The curves in FIGS. 3 and 4, represent gains in the powder mass produced by propulsive charges according to the invention, in accordance with parameter R associated particularly to the more or less slender powder strands. The various curves depend upon the rate of combustion of the selected powder.

FIG. 3 shows the variation of G in terms of R for various values of λ .

Curves 1, 2, 3, 4, 5 and 6 correspond to the following respective values of $\lambda=0.1; 0.2; 0.3; 0.4; 0.5$; and 0.6.

The curve G is bounded by the increasing values of R , since it is physically necessary that the thickness e remains positive or zero. The variation V' for a zero limiting thickness is represented by the expression:

$$K_1 \Sigma_t \frac{e_0 - e_0^2 \frac{K_1}{4\beta}}{2\beta l} \quad (7)$$

The variation of G is then represented by the curve f , whose algebraic formula is:

$$\frac{(4R-1)(2R+1)}{8R^2}$$

The points A, B, C on curves 6, 5, 4 correspond to these limiting points.

FIG. 4 represents the curves 1, 2, 3 and f for larger variations of R . The points D, E, F are the limiting points of the curves 3, 2 and 1.

It is further shown that the curves G corresponding to values of λ lying between 0 and 1 are located between the x -axis and the curve g given by the expression:

$$g = \frac{2R+1}{2R} [2R+1 - \sqrt{4R^2+1}]$$

Curves f and g differ very slightly for R greater than 2.5 and are accordingly represented by a single curve.

As an application of the results obtained above, there can be examined the case of a propellant charge meeting the conditions hereunder, these conditions being drawn from the antitank missile practice.

Constriction $K_1=550$

Constriction $K_2=275$

Coefficient of appropriate constriction $\beta=1.5$

Maximum thickness $e=0.5$ mm.

Overall length $l=150$ mm.

The coefficient R defined by Equation 5 equals 0.818.

For that value of R , the maximum gain possible is 15.8%. That corresponds to a value of λ comprised between 0.4 and 0.5. For the value of $\lambda=0.4$, the corresponding gain is 15.5%.

The value of $\lambda=0.4$ will be adopted, giving appreciably the possible maximum gain and less than K_2/K_1 .

The choice of λ defines the length b and strip thickness function, namely: $b=60$ mm.; $e_1=0.17$ mm.

The choice of the value K_1 for initial constriction defines the space between strands along the uniform thickness section, that is $i=0.5$ mm.

The values b , e_1 and i in combination with the starting hypotheses define fully the propellant charge.

This proves that it is possible to get appreciable gains of the order of 15%, on the initial velocity of antitank high-performance missiles by adopting a charge according to the invention.

More specifically, calculation of the coefficient R facilitates an assessment of the impulse gain to be expected, the maximum value being about 17% for a propellant charge made up of strips. The most significant gains are obtained for large values of $1/e$, account being taken of the practical limitations of length to small thicknesses corresponding to combustion times of less than 1 second.

The principal applications of the invention are to missiles or rockets comprising a short-combustion propellant stage, gas generators, this however not being restrictive of its scope.

The field covered by the invention comprises under the head of new industrial products, propellant charges complying with the foregoing specification, and products or systems utilizing such charges.

What is claimed is:

1. A propulsive charge comprising a plurality of spaced powder strands each including a portion of constant thickness and a tapered portion with a thickness de- 30

creasing progressively in the direction of gas discharge flow, said strands being composed of a double base powder of nitroglycerine and nitrocellulose.

2. A propulsive charge according to claim 1 wherein said strands are flat.

3. A propulsive charge as claimed in claim 1 wherein the powder strands are constituted by cylindro-conical tubes.

4. A propulsive charge as claimed in claim 1 wherein the decrease in the thickness of the powder charge is linear.

5. A propulsive charge as claimed in claim 1 wherein said strands provide a constriction K in a plane perpendicular to gas flow, the thickness decreasing in straight line proportion to the length x according to the relation

$$e = e_0 \frac{2\beta x}{K}$$

wherein β is a constant.
